SERVING SPOON OR SIMILAR ARTICLE

Robert A. Eckersberg and James L. Hvale, Chicago, Ill.,
assignors to Ekco Products Company, Chicago, Ill., a
corporation of Delaware

Filed Mar. 22, 1961, Ser. No. 64,434

Term of patent 14 years

(Cl. D44—29)

FIG. 1 is a front elevational view of a serving spoon or similar article showing our new design.

FIG. 2 is a side elevational view thereof.

FIG. 3 is a rear elevational view thereof.

FIGS. 4, 5, 6 and 7 are enlarged transverse sectional views taken along lines 4—4, 5—5, 6—6, and 7—7 respectively of FIG. 1.

The essential features of our design are shown in full lines.

We claim:

The ornamental design for a serving spoon or similar article substantially as shown and described.
